FURNACE PORT CONSTRUCTION

Karl G. Kutchka, Wilkinsburg, Pa., assignor to
 Pittsburgh Plate Glass Company, Allegheny
 County, Pa., a corporation of Pennsylvania

Application March 4, 1938, Serial No. 193,958

8 Claims. (Cl. 263—15)

The invention relates to a furnace port construction and particularly to the means for supplying gas thereto for giving the proper mixture with the heated air flowing through the port from the regenerators. The present practice inclines toward the use of wider ports and considerable difficulty is encountered in securing a thorough distribution of the combustible gas throughout the relatively large cross section of air flowing 5 through the ports. The failure to secure a complete mixture results in poor combustion in the furnace even though the relative proportions of gas and air supplied are theoretically correct.

The present invention has for one of its principal objects the provision of a port and burner construction which will insure a very complete mixture of the gas and air with wide port openings which may range in width (horizontally) up to six feet, and thus insure a more efficient 10 combustion in the furnace. A further object is the provision of a simple construction suitable for standard installations in which combustion will begin at or close to the port opening rather than back of the port opening as has been proposed 15 heretofore in attempts which have been made to secure the same end result of a complete mixture of gas and air, since combustion in the port passage remote from the outlet end results in heat losses and reduces the life of the flue walls which 20 are thus overheated. One embodiment of the 25 invention as applied to a glass tank or furnace is illustrated in the accompanying drawings, 30 wherein:

Figure 1 is a vertical section through one side 35 of the tank or furnace equipped with the improved apparatus. Fig. 2 is a horizontal section on the line II—II of Fig. 1. And Fig. 3 is an end elevation of the port opening showing diagrammatically the distribution of the combustible gas 40 therein as provided by my apparatus.

Referring to the drawings, 4 is the melting end 45 of a glass tank, and 5 is one of the port openings leading through the side wall of the tank. It will be understood that the other side of the tank 50 involves a similar construction and that there are a number of port openings similar to the opening 4 on each side of the tank. Two sets of checkerwork chambers 6 and 7 are provided on each side of the tank, in which the air to be delivered to the tank is preheated. The passages 8 and 9 lead upward from the checker chambers and discharge horizontally through the passages 10 and 11, such passages being separated by a partition wall 12, which terminates about three feet short of the port opening 5. The top wall 13

of the passageway forward of the division wall is inclined downwardly, as indicated in Fig. 1, to direct the mixture of air and gas flowing through the passageway downward toward the surface of the material in the tank, which in this instance, 5 is glass. This expedient is one which is known in the art and increases the efficiency of the apparatus. The side walls 14, 14 of the passageway are preferably inclined toward each other from the port opening 5 back so that the volume of 10 gas and air is spread out laterally due to the port opening being of greater width than height, as indicated in Fig. 3. As heretofore pointed out, the present practice tends toward the use of wide 15 ports which may range in horizontal dimension as much as six feet.

The method of supplying the combustible gas to the passageway to the rear of the port opening 5 will be seen by reference to Figs. 1 and 2. As here shown, the side walls of the passageway 20 are provided with two pairs of gas passages 15, 15 and 16, 16, through which gas is supplied from the pipes 17, 17 and 18, 18. The pair of passages 15, 15 are adjacent the port opening 5 and the bottom of the passageway, while the passages 16, 25 16 are located at the end of the division wall 12, so that the gas which flows through these passages is supplied to the body of air flowing through the passageway intermediate the two layers flowing through the passages 10 and 11. 30 Both sets of gas passages 15, 15 and 16, 16 are directed at an angle transverse to the longitudinal center line of the passageway and also toward the port opening, the angle of the passages 15, 15 with respect to the line of flow being more acute 35 than the angle of the passages 16, 16 with respect to such line of flow. As a result the gas supplied through the passages 15, 15 is distributed through the port opening, as indicated in the shaded portions of the drawing marked A, A, in Figs. 2 and 40 3, such areas being the ones along the sides of the passageway. The gas passing through the passages 16, 16 is directed to the center of the body of air flowing through the passageway, as indicated by the shaded areas marked B, B, in 45 Figs. 2 and 3, so that the central portion of the body of air receives its supply of gas from the passages 16, 16. The location of the passages 16, 16 and their angle with respect to the line of flow contribute to the distribution of the gas to the 50 central portion of the body of air flowing through the port, but in addition, this tendency towards central distribution may be increased by supplying gas through the pipes 18, 18 at a higher pressure than that supplied through the pipes 17, 17. It 55

will be seen that by the foregoing arrangement, provision is made for distributing gas effectively throughout the entire width of the port area even though such area is relatively wide in a horizontal direction, and that there are no portions of the cross section which are not supplied with gas. As a result, a very thorough distribution of gas and air occurs, and a consequent high efficiency is secured in the combustion which subsequently occurs. The low pressure which is preferably used in the gas pipes 17, 17 carries the gas forwardly at a velocity such that combustion occurs closer to the side walls of the port opening 5 than would be the case if high pressure were used in these supply pipes. This is desirable as heretofore pointed out, in that this combustion at or closely adjacent the port opening gives greater efficiency and avoids any tendency of overheating the walls of the port passageway back from the port opening. Other advantages incident to the construction will be apparent to those skilled in the art.

What I claim is:

1. In combination in a furnace having means for preheating the air used for combustion and a horizontally elongated port opening, a passageway for conducting the heated air to the opening, such passageway having its top wall inclined upwardly from the horizontal from the port opening back a substantial distance, a pair of gas passages through the side walls of the passageway adjacent the port opening and the bottom of the passageway, a second pair of gas passages through the side walls of the passageway 35 to the rear of the first pair of passages and at a higher level than such passages, and gas supply pipes for delivering combustible gas under pressure through all of said passages, all of said pipes being positioned transverse to the longitudinal center line of the passageway and inclined so 40 that they deliver toward the port opening, with the angle of inclination of the pipes delivering through second pair of passages less with respect to the longitudinal center line of the passageway than that of the pipes delivering 45 through the other pair of passages.

2. In combination in a furnace having means for preheating the air used for combustion and a horizontally elongated port opening, a passageway for conducting the heated air to the opening, such passageway having its top wall inclined upwardly from the horizontal from the port opening back a substantial distance, a pair of gas passages through the side walls of the passageway adjacent the port opening, a second 50 pair of gas passages through the side walls of the passageway to the rear of the first pair of passages and at a higher level than such passages, means for supplying combustible gas under pressure through the first passages at an angle transverse to the longitudinal center line of the passageway and also toward the port opening, and means for supplying combustible gas at a higher pressure through the second 55 passages at a more obtuse angle to said center line than the discharge through the first passage.

3. In combination in a furnace having means for preheating the air used for combustion and a horizontally elongated port opening, a passageway for conducting the heated air to the opening, a horizontal division wall in the passageway terminating short of the port opening a substantial distance, a pair of gas passages through the side walls of the passageway adjacent 60 the port opening, a second pair of gas passages

through the side walls of the passageway opposite the end of said division wall and at a higher level than the first pair of passages, and gas supply pipes delivering combustible gas through all of said passages.

4. In combination in a furnace having means for preheating the air used for combustion and a horizontally elongated port opening, a passageway for conducting the heated air to the opening, such passageway having its top wall inclined upwardly from the horizontal from the port opening back a substantial distance, a horizontal division wall in the passageway terminating short of the port opening a substantial distance, a pair of gas passages through the side walls of the passageway adjacent the port opening, a second pair of gas passages through the side walls of the passageway opposite the end of said division wall and at a higher level than the first pair of passages, means for supplying combustible gas under pressure through the first pair of passages, and means for supplying combustible gas at a higher pressure through the second pair of passages.

5. In combination in a furnace having means for preheating the air used for combustion and a horizontally elongated port opening, a passageway for conducting the heated air to the opening, such passageway having its top wall inclined upwardly from the horizontal from the port opening back a substantial distance, a horizontal division wall in the passageway terminating short of the port opening a substantial distance, a pair of gas passages through the side walls of the passageway adjacent the port opening, a second pair of gas passages through the side walls of the passageway opposite the end of said division wall and at a higher level than the first pair of passages, means for supplying combustible gas under pressure through the first pair of passages, toward the port opening at an acute angle to the line of flow of air through the passageway, and means for supplying combustible gas at a higher pressure through the second pair of passages toward the port opening and at a less acute angle to said line of flow than in the case of the first pair of passages.

6. In combination in a furnace having means for preheating the air used for combustion and a horizontally elongated port opening, a passageway for conducting the heated air to the opening, such passageway having its top wall inclined upwardly from the horizontal from the port opening back a substantial distance, and having its side wall inclined toward each other from the port opening back a substantial distance, a pair of gas passages through the side walls of the passageway adjacent the port opening, a second pair of gas passages through the side walls of the passageway to the rear of the first pair of passages and at a higher level than such passages, and gas supply pipes for delivering combustible gas under pressure through all of said passages.

7. In combination in a furnace having means for preheating the air used for combustion and a horizontally elongated port opening, a passageway for conducting the heated air to the opening, such passageway having its top wall inclined upwardly from the horizontal from the port opening back a substantial distance, a horizontal division wall in the passageway terminating short of the port opening a substantial distance, and having its side walls inclined toward each other from the port opening back a substantial distance, a pair of gas passages through the side walls of the passageway adjacent the port open-

ing, a second pair of gas passages through the side walls of the passageway opposite the end of said division wall and at a higher level than the first pair of passages, and gas supply pipes delivering combustible gas through all of said passages.

8. In combination in a furnace having means for preheating the air used for combustion and a horizontally elongated port opening, a passageway for conducting the heated air to the opening, such passageway having its top wall inclined upwardly from the horizontal from the port opening back a substantial distance, a horizontal division wall in the passageway terminating short of the port opening a substantial distance, and

15 having its side walls inclined toward each other from the port opening back a substantial dis-

tance, a pair of gas passages through the side wall of the passageway adjacent the port opening, a pair of gas passages through the side walls of the passageway opposite the end of said division wall and at a higher level than the first pair of 5 passages, means for supplying combustible gas under pressure through the first pair of passages toward the port opening at an acute angle to the line of flow of air through the passageway, and means for supplying combustible gas at a higher 10 pressure through the second pair of passages toward the port opening, and at a less acute angle to said line of flow than in the case of the first pair of passages.
